C. Ashworth & Co.

UNITED STATES PATENT OFFICE.

ELIAS A. SEALE, OF BREWTON, ALABAMA, ASSIGNOR TO THE ALABAMA METAL WHEEL COMPANY, OF SAME PLACE.

WHEEL.

SPECIFICATION forming part of Letters Patent No. 439,359, dated October 28, 1890.

Application filed March 13, 1890. Serial No. 343,730. (No model.)

To all whom it may concern:

Be it known that I, ELIAS A. SEALE, a citizen of the United States, residing at Brewton, in the county of Escambia and State of Alabama, have invented a new and useful Wheel, 5 of which the following is a specification.

This invention has relation to improvements in metal wheels for vehicles of all classes, though especially designed to be employed in the construction of light road buggies and carriages.

Among the objects of the invention are to obviate the employment and necessity of a tire, to lighten the spokes and in fact the entire structure as a whole, to improve the manner of connecting the spokes with the hub and band and so mount the same as to draw from the hub toward the rim, to deaden any ring of the spokes, and to provide an improved connection between the hub and spokes, and a means for continuously oiling the bearings.

With the above general objects in view the invention consists in certain features of construction, hereinafter specified, and particularly pointed out in the claims.

Referring to the drawings, Figure 1 is an elevation of a wheel constructed in accordance with my invention. Fig. 2 is a vertical circumferential section. Fig. 3 is a transverse section. Fig. 4 is an enlarged detail of Fig. 2, portions being broken away. Fig. 5 is a detail in perspective of the inner end of one of the metal spokes. Fig. 6 is a transverse section of the rim, illustrating a modified construction thereof. Fig. 7 is a similar view of the preferred construction of rim.

Like numerals of reference indicate like parts in all the figures of the drawings.

In practicing my invention I employ a cylindrical box 1, provided with the two bearing portions 2, intermediate which is the annular channel 3. The box 1 at its inner end is provided with the axle embracing band or flange 4, and at the juncture of the band and box with the laterally-disposed annular flange 5. The opposite end of the box is exteriorly threaded, as at 6, and over the same there is mounted a dust-cap 7, which also performs the double function of an oil-reservoir, and

for the purpose of receiving the liquid lubricant is provided beyond the end of the box with an oil-port 8, having a threaded plug 9 removable therefrom. The interior of the cap is provided with a screw-thread 10, for engaging the threads 6 upon the exterior of the box 1, and at its inner end the cap is provided with an external angular surface 11, adapted to receive and provide a bearing for an ordinary wrench, by which, as will hereinafter appear, the hub-sections are securely bound in position.

The hub proper is preferably cast in two circumferentially-divided sections, and each of said sections consists of a cylindrical shell 65 centrally bored, as at 12, and between its inner and outer peripheries annularly grooved, as at 13, thereby forming an outer and inner annular flange 14 and 15, respectively. This groove and flanges occur upon the outer face 70 of each of the shells, as is apparent. The shells are secured together by simply drilling through the bottoms of the grooves and inserting transverse dowels or rivets 15. (See Fig. 4.) By this means the two sections 75 constitute a single and apparently integral shell, though for the purpose of casting with convenience I form them as described.

The inner and outer flanges of each of the shells are provided with radially-disposed 80 spoke-receiving sockets 16, which sockets are of dovetailed form, the largest portion of the socket occurring at the inner periphery of the shell and the smallest portion at the outer periphery. The sockets of one section, or occurring at one side of the shell, occur opposite the space between the sockets of the opposite section or at the opposite side of the shell, or, in other words, they alternate, as do the spoke-sockets of the ordinary wooden wheel.

Referring more particularly to Fig. 7, 17 represents the rim, which in cross-section is of triangular shape, the same consisting of an outer base or tread 18, perfectly flat and being formed by the base of the triangle. In this 95 instance I do not employ any further guard for the rim; but the rim 17, being formed of metal, serves the double function of a rim and also of a tire. Instances, however, will occur in which it is desirable to employ tires prin- 100

cipally for the purpose of deadening the sound caused by the metal wheel, for which rubber is usually employed. To meet such contingencies, therefore, I have illustrated in Fig. 6 5 a slightly-modified construction of rim, whereby the same is adapted for the reception of such sound-deadening tire.

19 represents a rubber tire, preferably of elliptical shape in cross-section and its longer 10 diameter being somewhat less than the width of the rim 17, which rim has its periphery provided with a shallow groove 20, conforming to the shape of the tire and at its edges projecting beyond the sides of the tire, as at 21, 15 thereby serving the purpose of protecting flanges, so that when the wheel strikes upon the edges of stones or other obstructions calculated to abrade the same the rim or flanges 21 will take abrasion or deflect the stone out 20 of the course of the wheel. In the modified construction I provide the shallow groove or channel 20 with outwardly-projecting lugs 22, which lugs correspond with and take into cavities 23, formed in the inner surface of the 25 rubber tire. The rim 17 is formed right angular in cross-section, so as to reduce to a minimum the amount of metal therein, while at the same time to avoid sacrificing the strength and rigidity of the rim. The rim is formed 30 in a single piece, the ends being lapped and welded, as is common in metal rims.

24 represents the spokes, also of metal, and from points near their entrance into the hub-socket to points near their entrance in the 35 rim-socket, said spokes in cross-section are of diamond shape, as shown in Fig. 5. The diamond-shaped spoke is possessed of many advantages. The length of the diamond is disposed laterally, so that an extremely good 40 effect is given to the wheel thus constructed. Furthermore, the spokes are tapered, so that they are thicker or heavier at their bases or inner ends. The diamond shape also possesses the advantage of an economy in the material used and induces likeness, as by practical experience I have found that a spoke of this shape possesses all the rigidity and strength of a cylindrical spoke the diameter of which is equal to the greatest width in cross- 45 section of the diamond-shaped spoke, so that, as will be apparent, a great saving of metal, and therefore cost and weight, is effected. The outer extremities of the spokes are reduced to form threaded tenons 25, which tenons 50 enter threaded sockets 26, formed in the rim at intervals, said sockets being formed in what would be the angle of the triangle.

27 represents a series of rubber sleeves, which are sprung over the ends of the spokes, 60 and fitting the upper portions of the threaded tenons are forced against the inner periphery of the rim, so that they prevent any rattling or metallic sound issuing from the spokes during the revolutions of the wheel. The inner 65 ends of the spokes are rectangular in cross-section and are reduced from the beginning of the tenon 28 to the base, so that in vertical

transverse section they are dovetailed and correspond with the dovetailed recesses 16 of the hub-sections.

The manner of inserting the spokes in the wheel and placing the same under tension is as follows: The outer tenons are threaded in the sockets 26 until the inner ends or dovetailed portions 28 of the spokes register with the dovetailed recesses 16 of the flanges 14 and 15. The butts or tenons 28, after being thrown into register with said dovetailed recesses, are now driven laterally into the same by a hammer. After the spokes have been thus mounted in position the box 1 is inserted through the opening 12 of the hub-shell, and the annular flange 5 of said box takes against the series of spokes set into the dovetailed recesses of the inner shell-section. After this 85 an annular flange 29 is inserted over the end of the box and against the opposite shell-section. The dust-cap 7 is now mounted over the end of the shell or hub, and the inner end of the same binds against the outer face of 90 the annular flange. A large wrench is now applied to the nutted surface of the dust-cap and great power applied to the wrench, by which said dust-cap is securely bound against the flange and the flange against the hub-section and the spoke-tenons. This completes the construction of the wheel, and the axle is mounted in the same in the usual manner, the dust-cap serving the function also, and as before stated, of an oil-reservoir, and being partially or wholly filled with oil the lubricant is gradually fed to the interior of the hub, and I thus obviate the necessity of any frequent removal of the wheels from the axle for the purpose of oiling the same.

Having thus described my invention, what I claim is—

1. In a wheel, the combination, with a hub-section having its opposite faces provided with dovetailed recesses, said recesses having their side walls converged toward their outer ends, and a rim having threaded spoke-sockets, of a series of spokes, the outer ends of which are reduced to form threaded tenons for engaging the sockets of the rim, and the opposite ends of which terminate in dovetail-shaped butts or tenons fitting the recesses of the hub-section, substantially as specified.

2. In a metal wheel, the combination, with the hub, rim, and a series of metallic spokes removably connected with the rim at their outer ends, of rubber sleeves, as 27, mounted on the spokes at their junction with the rim, substantially as specified.

3. The box 1, having the bearings 2 and the integral flange 5, and at its opposite end exteriorly threaded, as at 6, in combination with the hub-section, the opposite faces of which have dovetailed recesses radiating 130 therefrom, the spokes 24, having the dovetailed butts or tenons 28 entering the recesses, the rim 17, having the threaded opening 26, the spokes being tenoned and threaded, as at

25, for entrance into said sockets, the removable annular flange 29, and the dust or binding cap 7, threaded on the box 1 and having the nutted surface 11, substantially as specified.

4. The combination, in a metal wheel, with the central hub-section having a central bore for the reception of the axle, and between its inner and outer peripheries having an annular groove 13, forming inner and outer annular flanges upon each side of the section, said flanges being provided with dovetailed re-

cesses 16, the outer flanges being reduced, of the spokes terminating at their inner ends in gradually-enlarged butts or tenons, adapted 15 to fit the recesses 16, substantially as specified.

In testimony that I claim the foregoing as my own I have hereto affixed my signature in presence of two witnesses.

ELIAS A. SEALE.
